CENTRAL BUFFING AND DRAFT GEAR

Richard Thomson Glascodine, London, England

Application June 29, 1931, Serial No. 547,702,
and in Great Britain September 16, 1930

4 Claims. (Cl. 213—50)

This invention relates to central buffing and draft gear for railway vehicles.

With central buffing and draft gear hitherto in use the lateral component of the blow resulting from impact between vehicles on a curve is transmitted to the vehicle underframe directly by the front follower plate or equivalent member of the gear bearing on one of the main longitudinal sills or on a casting attached thereto.

10 Much has been done to moderate the main longitudinal fore and aft blows on impact.

The main object of the present invention is to provide suitable means for cushioning or reducing the intensity of the lateral stress produced by such blows. Further and favourable objects will appear from the following description.

In central buffing and draft gear according to the invention side cushions of india-rubber or other suitable material are provided resiliently mounting the gear as regards lateral movement and operative to cushion lateral stress when buffing on curves.

25 Preferably, between the follower plates or equivalent longitudinally movable members of the gear and the centre sills of the vehicle or the rigid castings attached thereto, there is interposed at each side of the gear a liner plate or liner plates having little or no longitudinal movement and between such liner plates and the centre sills or castings appropriately shaped pads preferably of india-rubber are provided which form a lateral cushion between the draw gear and the vehicle underframe.

35 Other vibration absorbing material than rubber may be used, but at the present time vulcanized india-rubber is the best medium known for moderating impact stress and eliminating molecular vibration which even when not of excessive intensity, as is the case with the lateral component of the blows to which railway vehicles are normally subjected, tend to fatigue and depreciate the structure rendering it less efficient for duty under direct stress.

45 In a preferred embodiment of the invention applied to central buffing and draft gear of the type including a yoke connected to the rear of the coupler shank through a single cotter and slot, the liner plates, according to the invention, 50 with the associated rubber pads, are secured to the inner faces of the centre sills so as to form bearing surfaces for the follower plates located within the yoke and operating the springs or friction blocks constituting the cushion for the 55 main fore and aft blows.

The liner plates conveniently extend longitudinally of the vehicle from the front follower plate abutments to the rear abutments, whereby longitudinal movement of the liner plates is prevented, the liner plates being secured to the vehicle sills by nuts and bolts passing transversely through the vertical walls of the sills, the bolt heads being recessed or countersunk in the liner plates.

60 Where the buffing and draft gear includes a plurality of springs arranged tandemwise or in column form, for instance where a pair of india-rubber springs are arranged tandemwise on a draw rod connected to the rear of the coupler shank, two sets of liner plates with associated 70 india-rubber pads may be provided, the front set being juxtaposed to the front vehicle abutments and forming lateral bearing surfaces for the front follower head, and the second pair of liner plates 75 with associated india-rubber pads being located immediately in front of the rear vehicle abutments and constituting lateral bearing surfaces for the rear follower plate mounted on the rear end of the draw rod.

80 To restrain the liner plates against longitudinal movement small abutment blocks can be secured to the centre sills at the ends of the liner plates remote from the main vehicle abutments, such blocks being removably secured to the centre 85 sills by nuts and bolts and being formed with guide surfaces permitting free lateral movement of the liner plates.

Reference will now be made to the accompanying drawings which illustrate by way of example 90 several embodiments and in which:—

95 Figs. 1, 2 and 3 illustrate the application of the invention to draft gear embraced within a yoke, Fig. 1 being a vertical section, Fig. 2 a part sectional plan, and Fig. 3 a transverse section on the line III—III of Fig. 1, showing the vertical extent of the liner plates provided according to the invention and secured to the inner surfaces of the centre sills.

100 Figs. 4, 5 and 6 illustrate a further embodiment of the invention to draft gear including a plurality of springs arranged tandemwise on a draw rod pivoted to the rear of the coupler shank, Fig. 4 being a longitudinal section, Fig. 5 a horizontal section, and Fig. 6 a transverse vertical section 105 on the line VII—VII of Fig. 4.

110 Referring to the drawings, but first more particularly to Figs. 1 to 3, 1 designates the coupler head and 2 the coupler shank slotted at 3 to receive a draft key 4 passing transversely through

the slot 3 and through slots 5 in the forwardly extending arms 6 of the yoke 7.

The rear end 8 of the coupler shank 2 is formed with a vertical pivot for a pin 9 which is borne by the follower head 10 of the front follower plate 11 providing the usual arrangement in which the coupler head 1 is permitted limited lateral movement in regard to the vehicle, for example when coupling or when rounding curves.

10 The rear end of the yoke 7 engages the rear follower plate 12, and the centre sills 13 and 14 of the vehicle underframe carry front abutments 15 for the front follower plate 11 and rear abutments 16 for the rear follower plate 12.

15 17 represents the cushioning element of the draft gear located between the front and rear follower plates 11 and 12, the gear operating to cushion the main longitudinal fore and aft blows in the usual manner; for instance under draft stress the coupler—operating through the draft key 4—pulls the yoke 7 forwardly, and the yoke 7 engaging the rear follower plate 12 transmits the thrust through the cushioning element 17 of the gear and the front follower plate 11 to the vehicle by way of the fixed abutments 15.

Under buffing stress the coupler shank 2 moves rearwardly and operates the front follower plate 11 to compress the cushioning element 17 against the rear follower plate 12 which bears against the fixed rear abutments 16.

According to the invention a cushion for any lateral stress is provided in the form of liner plates 20 which are shown mounted on the inner surface of the centre sills 13 and 14 extending between the front and rear abutments 15 and 16 and which form bearing surfaces for each side of the follower plates 11 and 12.

21 represents pads of india-rubber or other appropriate cushioning material interposed between the liner plates 20 and the inner face of the centre sills 13 and 14, and 22 are bolts having countersunk heads 23 which bolts pass transversely through the liner plates 20, the india-rubber pads 21 and the vertical wall of the centre sill, and are secured by nuts 24.

Any desired initial compression of the india-rubber pads 21 can be effected by adjusting the nuts 24 on the bolts 22, six of which are shown for each liner plate 20, eliminating any possibility of the liner plates 20 rocking under stress.

50 The follower plates 11 and 12 are of rectangular form and are provided with peripheral flanges 26 and 27 respectively giving an enlarged bearing surface in contact with the liner plates 20 and preventing any tendency of the followers to rock under stress.

The initial compression of the india-rubber pads 21 is conveniently such that lateral movement of the follower plates 11 and 12 bearing on the liner plates 20 is substantially eliminated even under the most intense lateral stress likely to be experienced, but it will be seen that the interposition of such rubber pads prevents the direct transmission of such stress to the underframe of the vehicle and constitutes a cushion moderating impact stress and eliminating molecular vibration which even when not of excessive intensity tends to fatigue and depreciate the structure.

The customary guide or bearer for the yoke 7 is shown in Fig. 3 at 25 and bridges the under-side of the two centre sills 13 and 14.

70 Referring now to the embodiment of the invention illustrated in Figs. 4 to 6, the rear end of the coupler shank 50 is pivoted to a draw rod 51 on which are mounted tandemwise buffing and

80 draft springs generally designated 52 and 53, buffing thrust being applied to the springs through the front follower head 54 engaged by the rear of the coupler shank 50, and draft stress being applied to the gear through a rear follower plate 55 engaged by a nut 56 mounted on the rear end of the draw rod 51. 57 and 58 are front and rear abutments for the follower plates 54 and 55 respectively, and are secured to the centre sills 59 by rivets, as is customary.

85 With this embodiment of the invention a front pair of liner plates 60 are provided for the front follower head 54 and are resiliently mounted on india-rubber pads 61, while for the rear follower plate 55 a second pair of liner plates 62 are provided with interposed india-rubber pads 63.

90 The liner plates 60 and 62 are mounted on the inner faces of the centre sills and are secured in position as described in connection with the first embodiment, the liner plates 60 on which the front follower head 64 bears taking the bulk of the lateral thrust incident on buffing when the coupled vehicles are on a curved portion of the track and such thrust being cushioned by the interposed india-rubber pads 61, while the rear 100 plates 62 with their resilient cushions 63 operate to a less extent to cushion lateral thrust and serve to remove any possibility of end to end vibration being produced in the draft gear as a result of stress, thereby ensuring silence in operation.

105 The front liner plates 60 are shown immediately behind the front vehicle abutments 57, rearward movement of the liner plates 60 being prevented by stops 64 secured to the centre sills by nuts and bolts 65, while, conversely, the rear liner plates 62 are located immediately in front of the rear abutments 58 and are prevented from forward movement by stops 66 secured by nuts and bolts 67.

110 With this construction the springs constituting the cushioning elements 52 and 53 of the gear are of general circular form, the rear spring 53 being located within a housing comprising a cylindrical flange 68 on the rear follower plate 55, the casing being formed with a step 69 having a 120 flat lower surface which rides the usual guide or bearer 70, as clearly shown in Fig. 7.

115 The followers 54 and 55 are arranged with vertical side walls giving adequate bearing surface in contact with the liner plates 60 and 62, 125 the follower 54 being a webbed casting having its rear face abutting with a tubular sleeve 71, which, in conjunction with an outer sleeve 72 co-operating with the annular flange 68 on the rear follower plate serves to effect compression of 130 both springs 52 and 53 in parallel.

120 It will be understood that the embodiments of the invention illustrated are given by way of example and that modifications may be made within the scope of the appended claims.

125 By the present invention the shocks transmitted to the vehicle underframe are considerably reduced and the durability and silence in running of vehicles equipped with the lateral cushions thereby enhanced.

130 What I claim is:—

1. In central buffing and draft gear, a coupler shank, front and rear followers disposed between the centre sills in rear of said shank, buffing and draft springs between said followers, liner plates secured to the centre sills forming lateral guides for said followers, and cushions of india-rubber interposed between said liner plates and the centre sills operative to prevent the transmission of lateral vibration and to cushion the lateral 150

- component of the impact stress when buffing on curves.
2. In central buffing and draft gear according to claim 1, flanges to said followers providing an enhanced bearing surface in contact with said liner plates.
3. In central buffing and draft gear according to claim 1, fixed vehicle abutments secured to the centre sills limiting the longitudinal travel of said followers and fixing the longitudinal location of said liner plates.
4. In central buffing and draft gear, a coupler shank, a draw rod having a head pivoted to the rear end of said shank, front and rear followers disposed on said draw rod between the centre sills, liner plates secured to the centre sills, one pair forming lateral guides for the front follower and a second pair forming lateral guides for the rear follower, and cushions of india-rubber interposed between said liner plates and the centre sills operative to prevent the transmission of lateral vibration from said shank to the vehicle and to cushion the lateral component of the impact stress applied through said shank when buffing on curves.
